PANEL METER

Roger B. Kerr, Topsfield, Mass., assignor to General
Electric Company, a corporation of New York

Filed Oct. 22, 1963, Ser. No. 77,095

Term of patent 14 years

(Cl. D52—6)

FIG.1

FIG.2

FIG. 1 is a perspective view of a panel meter of my new design; and

FIG. 2 is a side view of the panel meter of my new design.

The undisclosed side of the panel meter is substantially the same in appearance as the side shown.

The essential features of my disclosed design reside in the portions shown in full lines.

I claim:

The ornamental design for a panel meter, as shown and described.
